UNITED STATES PATENT OFFICE.

CHARLES T. WESTLAKE AND ALBERT R. THOMAS, OF ST. LOUIS, MISSOURI, ASSIGNEES TO
DAVIS LOCOMOTIVE WHEEL COMPANY, OF ST. LOUIS, MISSOURI, A CORPORATION OF
DELAWARE.

DRAFT-GEAR FOR LOCOMOTIVE ENGINES AND TENDERS.

No. 918,237.

Specification of Letters Patent.

Patented April 13, 1909.

Application filed July 16, 1908. Serial No. 443,861.

To all whom it may concern:

Be it known that we, CHARLES T. WESTLAKE and ALBERT R. THOMAS, citizens of the United States, residing at St. Louis, in the 5 State of Missouri, have invented a new and useful Improvement in Draft-Gear for Locomotive Engines and Tenders, of which the following is a specification.

Our invention relates to that class of draft-gear for a locomotive engine or tender in which the coupler is combined with a spring (or springs as the case may be) and follower-plates having their housing in, or attached to the pilot beam or end sill, and is in the nature 10 of an improvement on the invention for which application for Letters Patent of the United States was filed by William Bawden, and Albert R. Thomas March 11, 1908, Serial Number 420,518, for an improvement in 15 draft-gear for locomotive engines and tenders, in which the pulling stress of the coupler is transmitted through the limited engaging surface of its pivot-pin only, to the pilot-beam thereby rendering the latter liable to 20 fracture thereat and in such case necessitating its removal and renewal; and our invention has for its object to remove this objection 25 and to enable the coupler to be adjusted to its normal height from the rails without 30 the use of the shims described in the said application.

The invention consists in features of novelty as hereinafter described and claimed, 35 reference being had to the accompanying drawing forming part of this specification, whereon,

Figure 1, is a top plan view of our improved draft-gear as applied to a metallic locomotive pilot-beam broken away and shown 40 partly in horizontal section at its middle portion on line 1, 1, in Fig. 2; Fig. 2, a front elevation thereof, omitting the coupler indicated by dotted lines in Fig. 1, and Fig. 3, a vertical transverse section through the pilot-beam, and carry-iron for the coupler, on line 45 3, 3, in Fig. 2.

Like letters and numerals of reference denote like parts in all the figures.

a represents the pilot-beam or end sill 50 (broken away) of a locomotive engine or

tender, composed in the present case preferably, of cast steel integral throughout, and configured as shown, or otherwise as desired.

In the beam *a* at its middle portion, is formed a suitably shaped pocket *b* having 55 openings 1 and 2 respectively, through the front side and bottom of the beam *a*. Opening at its front end into the pocket *b* through its rear wall 3 (corresponding, or thereabout, to the rear side of the beam *a*) is a rearwardly extending horizontally arranged and preferably, cylindrical housing or chamber *c* which is closed at its inner or rear end and in central alinement with the longitudinal center of the underframe. 60

Within the housing *c* is a spiral spring *d* which is adapted to bear at one end against the inner closed end of the housing *c* and at its other end against the rear upright face of a follower-block *e* movable within the pocket 70 *b* to and from, and parallel to its rear wall 3, the follower-block *e* being adapted to bear on its front side adjacent to each lateral upright edge of the said face, against the rear side of preferably, an upright web (or analogous member) 4 which projects within the pocket *b* from the corresponding side wall 5 thereof at a suitable distance rearward from the front side of the beam *a*, and forms a stop to the follower-block *e*. 75

In the front portion of the follower-block *e* which projects forward between the webs or stops 4, through the front portion of the pocket *b* and the opening 1 through the front side of the beam *a*, is formed a horizontally 80 arranged jaw 6 adapted to receive the rear end of the coupler-shank (or draw-bar) 7 which is pivoted to the sides 6' of the jaw 6 by the vertically arranged pin 8, the rear end of the coupler-shank 7 being curved radially 90 to the pin 8 and adapted to bear in the horizontal movement of the coupler-shank 7 about the pin 8, against a correspondingly shaped portion of the follower-block *e* forming the bottom of the jaw 6. 95

Projecting from the bottom of each side wall 5 of the pocket *b* at and adjacent to the opening 1 through the front side of the beam *a*, is a channel-shaped bracket 9 having its flanges upward and adapted to be engaged 100

by the inverted correspondingly shaped end portions of a carry-iron 10 which spans the opening 1 thereat and is adapted to support the follower-block *e*, the metal at each side of 5 the carry-iron 10 projecting beyond the body and forming a shoulder which bears on the edges of the flanges of the brackets 9 and supports the carry-iron 10 in its engaged position therewith, the carry-iron 10 being held 10 in place by the follower-block *e* without the use of bolts or rivets. Between the brackets 9 and the overhanging bottom ends of the lateral portions 11 of the front wall of the beam *a* at the sides of the opening 1, sufficient 15 space or clearance is formed for enabling the carry-iron 10 to be raised for disengagement and removal from the brackets 9 without obstruction.

It is to be here noted that, the distance 20 from the longitudinal center line of the jaw 6 (or coupler-shank 7) between its sides 6' in the position of the parts shown on the drawing, to the bottom surface *x* of the follower-block *e* which bears thereat on the carry-iron 25 10, is less than the distance from the said center to the top surface *y* of the follower-block *e*, whereby, when from wear of the engine wheel-tires or other cause, the distance between the coupler-shank 7 and the rails of 30 the track become correspondingly reduced, the coupler-shank 7 can be restored to its normal standard height from the track by reversing the position of the follower-block *e*, or so that its top surface *y* bears upon the 35 carry-iron 10 in lieu of the bottom surface *x* as shown, sufficient space or clearance being left between the follower-block *e* in either of its said positions and the top of the pocket *b* for enabling the follower-block *e* with the 40 carry-iron 10 to be raised together for removing the latter from the brackets 9 in disconnecting the parts. It is also here noted that the rear face of the follower-block *e* along its upper and lower edge portions is 45 tapered or beveled, whereby, when the spring *d* is assembled within its housing *c*, on inserting the follower-block *e* through the bottom opening 2 of the beam *a* into the pocket *b* the beveled portions of its rear face 50 will compress the spring *d* sufficiently for allowing the follower-block *e* to be adjusted to its proper position between the spring *d* and the webs or stops 4 as shown.

In operation, assuming the spring *d*, the 55 follower-block *e*, and coupler-shank 7 to be in their normal position with the front side of the follower-block *e* bearing against the webs or stops 4 of the pocket *b* and engaged by the inner end of the coupler-shank 8, on "buffing" the coupler-shank 7 forces the follower-block *e* rearward so as to compress the spring *d* against the inner closed end of its housing *c* which transmits the stress to the

pilot-beam *a*, the rearward movement of the follower-block *e* being limited by the surrounding front edge of the housing *c* (or rear wall of the pocket *b*). 65

In "pulling", the spring *d*, follower-block *e*, and coupler-shank 7 are returned to their normal position by the resilience of the 70 spring *d* until the follower-block *e* is stopped by the webs or stops 4 by which the stress is transmitted through their extended bearing surface to the pilot-beam *a* in lieu of through the limited surface of the latter engaged by 75 the pivot-pin of the coupler-shank as in the said application.

What we claim as our invention and desire to secure by Letters Patent is:—

1. In draft-gear of the character described, 80 the combination with the pilot-beam and the coupler-shank, of a pocket in, and having a front opening through the said beam, a housing having an opening through its front end into the pocket and closed at its rear end, a 85 spring within the housing adapted to bear at its rear end against the closed end thereof, a follower-block within the pocket adapted to bear at its rear side against the front end of the spring and movable therewith to and 90 from the housing, limiting stops within the pocket adapted to be engaged by the follower-block in its forward movement, a jaw projecting from the follower-block and adapted to receive the rear portion of the 95 coupler-shank, a pin connecting the coupler-shank pivotally to the said jaw, and means for assembling and supporting the follower-block within the pocket, substantially as described. 100

2. In draft-gear of the character described, the combination with the pilot-beam and the coupler-shank, of a pocket in, and having a front opening through the said beam, a housing opening into the pocket, a 105 spring element within the housing, a follower-block within the pocket adapted to compress the spring element against the said beam, limiting stops integral with the said beam within the pocket and adapted to be 110 engaged by the follower-block on the recoil of the spring element, a pin connecting the coupler-shank pivotally to the follower-block, and means for assembling and supporting the follower-block within the pocket, 115 substantially as described. 110

3. In draft-gear of the character described, the combination with the pilot-beam and the coupler-shank, of a pocket in, and having a front opening through the said 120 beam, a housing having an opening through its front end into the pocket and closed at its rear end, a spring within the housing adapted to bear at its rear end against the closed end thereof, a follower-block within the pocket 125 adapted to bear at its rear side against the

front end of the spring and movable therewith to and from the housing, limiting stops within the pocket adapted to be engaged by the follower-block in its forward movement,
5 a jaw projecting from the follower-block and adapted to receive the rear portion of the coupler-shank, a pin connecting the coupler-shank pivotally to the said jaw, a carry-iron for the follower-block, and means for adjust-
10 ing the level of the coupler-shank relatively

to the bearing of the follower-block on the said carry-iron, substantially as described.

In testimony whereof we have signed our names to this specification in the presence of two subscribing witnesses.

CHARLES T. WESTLAKE.

ALBERT R. THOMAS.
